FIG. 6

FIG. 1 is a top plan view of an eye shadow kit showing my new design;

FIG. 2 is a front perspective view thereof with the lid in an open position;

FIG. 3 is an enlarged fragmentary sectional view taken along line 3-3 of FIG. 2 showing the grooved ornamentation on the outer surface thereof;

The dominant features of the design reside in the portions shown in full lines and the design is characterized by the cubist resemblance of the eye shadow blocks to a pair of human eyes and the heightening of this resemblance by the superpositioning of the pseudo spectacle ornamentation on the front cover of the kit.
